UNITED STATES PATENT OFFICE.

ANNA DEANE BAILEY, OF NEW YORK, N. Y., ASSIGNOR, BY DIRECT AND MESNE ASSIGNMENTS, TO G. H. MASTEN CO., INC., OF NEW YORK, N. Y., A CORPORATION OF NEW YORK.

LIFE-PRESERVER.

1,366,344.

Specification of Letters Patent. Patented Jan. 25, 1921.

Application filed August 16, 1918. Serial No. 250,214.

To all whom it may concern:

Be it known that I, ANNA DEANE BAILEY, a citizen of the United States, and a resident of the borough of Manhattan, city, 5 county, and State of New York, have invented certain new and useful Improvements in Life-Preservers, of which the following is a specification.

The main object of this invention is to 10 provide a jacket form of life preserver which is reversible, and which may be attached to the body very conveniently and quickly, and without confusion.

There are other important objects and 15 advantages of the invention, which will appear hereinafter.

In the drawings, Figure 1 is an elevation of the device in its open or extended position;

20 Fig. 2 a front view, showing the device applied;

Fig. 3 a rear view, showing the device applied;

25 Fig. 4 a detail vertical sectional view of the back portion of the device and the attached collar, taken on the line IV—IV of Fig. 3;

Fig. 5 a plan view of the device in its applied position;

30 Fig. 6 a horizontal sectional view of the device;

Fig. 7 a detail sectional view on the line VII—VII of Fig. 5; and

35 Fig. 8 a detail sectional view on the line VIII—VIII of Fig. 5.

Referring to the various parts by numerals, 1 designates the back section, and 2 and 3 the divided front section. The front sections are connected to the vertical edges of 40 the back section by flexible fabric portions 4. These connecting portions are preferably integral with the fabric which forms the front and back sections, but of course, they may be inserts, if desired. The fabric sections 4 are cut out at their upper ends as

45 at 5, to form the lower margins of the arm holes. The front sections are formed with vertical pockets, in which the buoyant material is arranged; and said vertical pockets

50 are divided to form the upper larger pockets 6, and the lower smaller pockets 7. These pockets may be of any desired size and shape, but I have found that this arrangement is very satisfactory, and enables 55 the front sections to be nicely fitted to the

body of the wearer. The back section is provided with the short vertical pockets 8, arranged along the upper edge thereof. These pockets are filled with buoyant material; and below the pockets the back section is formed with the flexible fabric apron 9. The pockets 8 are much shorter than the pockets 6 and 7 of the front sections; and the flexible apron 9 is provided so that the back section may be drawn closely in to the 60 back of the wearer, the apron hugging the wearer closely and preventing the buoyant section from rising around the wearer's neck. I have found that the flexible fabric apron clings nicely to the wearer when in 65 the water, and serves to securely hold the buoyant portion of the back section close to the wearer and prevents it lifting to an uncomfortable position.

The upper ends of the front and back 75 sections are connected together by flexible shoulder straps. These shoulder portions are preferably not padded with buoyant material, but of course, if desired, they may be so padded. The shoulder straps are cut 80 out, as at 11, to form the upper margins of the arm holes. These shoulder portions are preferably integral with the fabric which forms the front and back sections, but of course there may be additional pieces attached by stitching or otherwise, if desired.

Secured throughout the upper edges of the shoulder portions is a head-supporting pillow or collar 12, which is filled with buoyant material. Between the collar and 90 the shoulder portions is formed a tubular passage through which a draw-string 13 is arranged, the ends of said string projecting beyond the free edges of the front sections, as indicated clearly in Fig. 1. The purpose 95 of the draw-string is to enable the wearer to contract the collar about his neck; and the shoulder portions of the collar are sufficiently flexible to permit this to be readily done.

To secure the back portion and the front sections about the body of the wearer, two securing tapes 14, are employed, one near the upper ends of the sections and the other near the lower ends thereof. These tapes 105 are permanently secured to the back section and slide through loops 15, secured to the flexible inserts 4; and through loops 16, secured to the front sections. These tapes are preferably on the outer sides of the sections, 110

but it is quite immaterial whether they are on the outer side or the inner side when the device is in use. By drawing these tapes and securing their ends together, the body portions of the device may be accurately adjusted to the body of the wearer and the device made to fit snugly persons of various sizes.

To adjust the device for use it is only necessary to pass the arms through the arm-holes in the manner similar to putting on a jacket, and to then draw the strings 13 and the tapes 14 tightly and secure their ends together, as shown in Fig. 2. The device is reversible, and may be placed in position with either side toward the wearer. This is of great advantage for the reason that if in the confusion and excitement of placing the life preserver on the user should inadvertently place the securing tapes next to his body, it will not in any way interfere with the proper adjustment of the device or the proper operation of it. The device being in jacket form, the proper method of placing it in position is obvious, and no special directions are necessary. When the lower securing tape is drawn tightly the apron 9 is tightly drawn against the back of the wearer, as shown in Fig. 3, so that the device as a whole will be held securely in position, and may be prevented from rising when submerged.

What I claim is:—

1. A reversible jacket life preserver comprising a back section, two front sections connected to the vertical edges of the back section and formed with arm holes near their upper ends, flexible shoulder portions connecting the upper ends of said sections and formed with a tubular passage therethrough, a flexible collar connected to the shoulder portions, a neck-contracting tape passing through the tubular portion between the collar and the shoulder portions, and securing tapes connected to the front and back sections.

2. A reversible jacket life preserver, comprising a jacket part formed with arm holes and designed to be worn with either side out, and formed with a flexible shoulder part, a collar connected thereto, a tubular tape-receiving channel formed below the collar, a tape adapted to slide therein and contract the collar in the act of tying the collar around the neck of the wearer, and slideable contracting tapes connected to the body part and adapted to contract the body of the jacket in the act securing it to the body of the wearer.

3. A reversible jacket life preserver comprising a body part formed with arm holes, a flexible shoulder part and a flexible collar, and slideable contracting securing tapes connected to the shoulder part and to the body part, and adapted to contract the

jacket as a whole when tied to secure the jacket to the wearer.

4. A reversible jacket life preserver comprising a body part formed with arm holes, a flexible shoulder part and a flexible collar, and means for contracting the shoulder and body parts about the neck and body respectively of the wearer.

5. A life preserver comprising a body part, a collar connected thereto, said body part and collar being flexible and designed to be worn with either side out, and means for securing the body part and collar in closed position about the body of the wearer irrespective of which side of said body part and collar is out.

6. A life preserver comprising flexibly connected front and back buoyant sections disposed flatwise with reference to the body of the wearer and having similar opposite faces whereby the sections may be reversed in use, the front sections having buoyant means for maintaining the said front sections uppermost and the back section including a lower apron portion and an upper buoyant portion to support the body in water in an inclined position, a buoyant collar flexibly connected at one edge to said front and back sections and having both faces alike so that either face may be presented to the neck of the wearer, and fastening means for detachably connecting the front sections together and being accessible from either side.

7. A reversible jacket life preserver, having arm holes, comprising a body portion provided with buoyant material to give buoyancy to the jacket, a flexible collar provided with buoyant material to give buoyancy to the same, flexible front, shoulder and back portions connecting the lower ends of the collar with the upper ends of the body portion without buoyant material, and means for connecting the front ends of the body portion and the front ends of the collar, the jacket being alike on its inner and outer sides so as to be reversible and wearable with either side out.

8. A reversible jacket life preserver, having arm holes, comprising a body portion provided with a plurality of pockets each having buoyant material therein to give buoyancy thereto, flexible members between the pockets to enable the body portion to be reversed, a flexible collar provided with buoyant material to give buoyancy to the same, flexible portions connecting the collar with the body portion to enable the collar to be reversed, and means for securing together the front of the body portion and the front of the collar, the jacket being reversible and wearable with either side out.

In testimony whereof I hereunto affix my signature.

ANNA DEANE BAILEY.
